DESIGN FOR AN AUTOMOBILE RADIOCABINET

David Housman, Winthrop, Mass.

Application February 8, 1936, Serial No. 61,045

Term of patent 7 years

To all whom it may concern:

Be it known that I, David Housman, a citizen of the United States, residing at Winthrop, in the county of Suffolk and State of Massachusetts, have invented a new, original, and ornamental Design for an Automobile Radiocabinet, of which the following is a specification, reference being had to the accompanying drawing, forming a part thereof.

The figure is a view in perspective showing my new design. The opposite side portion of the cabinet is of the same configuration as the left-hand side shown in the drawing. The rear portion thereof is plain.

I claim:

The ornamental design for an automobile radiocabinet substantially as shown and described.

DAVID HOUSMAN.
